PIPE HANGER

Samuel S. Kolodin, New City, N.Y.

Application February 13, 1956, Serial No. 565,091

1 Claim. (Cl. 248—62)

This invention relates to a pipe hanger.

The present application involves an improvement over the pipe hangers which are disclosed in my co-pending patent application Serial No. 475,492 filed on December 15, 1954, now Patent No. 2,835,464.

A suitable pipe hanger is one which is strong enough to support a pipe with an ample safety factor, which is relatively inexpensive to produce, and which is very simple to use in connection with conventional pipe hanging methods and practices.

The conventional pipe hanger consists of an upper strap which is supported by a vertical rod or bolt from a ceiling or other support, a lower strap which carries the pipe, and a bolt which attaches the lower strap to the upper strap, including a nut. Thousands of pipe hangers are used in virtually every industrial building, warehouse and the like. In such quantities, the cost of the bolts alone becomes quite significant and in addition to that is the time consumed in inserting each bolt through said upper and lower straps and attaching a nut thereto. In a given installation, the time and labor consumed in inserting thousands of bolts and attaching thousands of nuts assume very substantial proportions. Consequently, the industry has long sought a pipe hanger which would eliminate the need of a bolt, which would be less costly than a conventional bolt-type pipe hanger, and which would be very simple to install without departing from conventional pipe hanging methods and practices.

It is the principal object of this invention to provide a two-piece pipe hanger which requires no bolts or other fastening means to secure the two parts together. One of these parts is a strap which is supported by a conventional bolt or rod from a ceiling or similar support. This strap corresponds to the upper strap of a conventional bolt-type pipe hanger and it is generally of inverted U-shape. The other part corresponds to the lower strap of a conventional bolt-type pipe hanger but it is not made of conventional strap material. Instead, it consists of a rod bent to generally U-shape with its upper ends bent inwardly and downwardly to form a pair of hooks. Holes for these hooks are provided in the upper strap member and in order to assemble said U-shaped rod to said strap member, all that need be done is to hook the upper ends of the U-shaped rod into the holes of the upper strap member, and the job is done.

An important feature of this invention is the means for removably locking the U-shaped rod in engagement with the upper strap member. This feature involves the provision of elongated holes in the upper strap member to receive the hook-shaped portions of the U-shaped rod. A pair of ears or lugs are pressed out of the metal of said upper strap member and into each of said elongated holes. These ears are engageable with the hook-shaped portions of said U-shaped rod to the extent that it becomes necessary to snap said hook-shaped portions past said ears in either direction. Accidental displacement of the U-shaped rods from said upper strap members becomes difficult, if not impossible, but when it is desired to remove them

2

from said upper strap members, all that need be done is to tap them with a hammer so as to by-pass the ears.

It will be understood that it is usually necessary to attach or detach said U-shaped rods while the pipe which they support or are intended to support remains elevated in its normally supported position or slightly above such position. A requirement of a suitable pipe hanger, therefore, is that it be mountable or demountable without any interference by or with such hanging pipe. In the use of the present pipe hanger, the upper strap member is secured to a sealing rod or bolt in conventional manner and a pipe is then held by temporary supports immediately below said upper strap member. This is also a conventional practice. And finally, the U-shaped rod is simply hooked into engagement with said upper strap member and the pipe may then be laid thereon. It is at this stage of the installation that the bolt-inserting and nut-engaging operation would normally take place but in the use of the present device said operation is entirely obviated.

The invention is illustrated in the accompanying drawing in which:

Fig. 1 is a side view of a pipe hanger made in accordance with one form of this invention, showing it supported by a vertical bolt from a suitable support.

Fig. 2 is an edge view thereof.

Fig. 3 is a side view of a modified form of U-shaped rod which may be used in conjunction with the upper strap member shown in Figs. 1 and 2.

Referring now to the first two figures of the drawing, it will be observed that pipe hanger 10, made in accordance with this invention, consists of two parts: An upper strap member 12 and a lower U-shaped rod 14. The upper strap member 12 is made of a flat bar of steel of suitable dimensions. For example, for relatively light work said strap may be made of one-eighth inch stock, perhaps an inch wide. For heavier work a quarter-inch bar would be required and for still heavier work an even heavier bar. The width of the bar would depend in great measure upon the diameter of the supporting vertical rod or bolt 16 since it is necessary to provide a hole 18 in the bar to receive said vertical rod or bolt. Said rod or bolt may be half an inch in diameter or thicker, depending upon the weight of the load to be supported thereby.

More specifically, strap 12 is provided with a central yoke portion 12a through which said hole 18 is formed. This central yoke portion is a relatively flat portion which normally occupies a substantially horizontal plane. It receives the rod or bolt 16 and upper and lower nuts 20 and 22 are screwed to said rod or bolt on opposite sides of said yoke to lock the strap 12 thereto. This is conventional.

Projecting outwardly and downwardly from the central yoke portion 12a is a pair of sloping shoulders 12b and 12c respectively. The angle of inclination of these shoulders may vary but in the preferred form of the invention they extend at an angle of approximately 45 degrees to the yoke portion 12a. The lower ends 12d and 12e of said shoulders are bent inwardly from the shoulders and toward the vertical.

It will be observed that openings 24 are formed in the two shoulder portions, one such opening in each shoulder. These openings are elongated longitudinally of the upper strap member and their width is determined by the diameter of the U-shaped rod 14. Projecting laterally into each opening 24 is a pair of ears or lugs 25 which are pressed out of the metal of which the upper strap member is made. The space between these ears is slightly smaller than the diameter of the U-shaped rod so that it becomes necessary to snap said U-shaped rod past said ears both when it is desired to engage said U-

shaped rod with the upper strap member and when it is desired to disengage it therefrom.

It will be observed that openings 24 are formed in the two shoulder portions, one such opening in each shoulder. These openings are tapered from relatively large proportions at their upper end to relatively small proportions at their lower end. The precise dimensions of these openings are determined by the dimensions of the U-shaped rod 14 and more particularly the diameter of said rod, as will shortly appear.

The U-shaped rod 14 consists mainly of a generally U-shaped lower portion 14a whose arms are bent outwardly and upwardly to form a double-bend 14b, a pair of upper arm portions 14c and 14d respectively, said upper arm portions extending from and above said double bend portions, and a pair of hook-shaped end portions 14e and 14f respectively which are formed at the upper ends of said upper arm portions 14c and 14d. The arms of the U-shaped portion 14a, below the double bend portions 14b, tend to diverge in upward direction so that they are farther apart immediately adjacent the double bend portions than they are at their lower ends. The size and curvature of said U-shaped portion 14a are dependent upon the diameter of the pipe to be supported thereby. The interrupted lines 30 designate a pipe adapted to be supported by the pipe hanger shown in the drawing. It will be understood that the diverging arms of the U-shaped portion 14a render it possible, if desired, to provide a wedging effect of the pipe between them. The weight of the pipe would wedge it into said U-shaped portion.

The upper arm portions 14c and 14d are disposed in generally vertical, parallel positions. They are offset by the double bend portions 14b from the lower U-shaped portion 14a so as to enable them to receive the upper strap member 12 between them, and more particularly its lower end portions 12d and 12e. This is an important feature of the invention since it provides sufficient clearance between the U-shaped rod 14 and the upper strap member 12 to render it possible to attach said U-shaped rod to or detach it from said upper strap member, while said upper strap member is fully secured to the support 16 and whether or not the pipe is held in position adjacent said upper strap member.

The hook-shaped portions 14e and 14f are simply the upper ends of the arms 14c and 14d bent inwardly and downwardly. When the U-shaped rod 14 is elevated a short distance above its Fig. 1 position, the hook-shaped portions 14e and 14f will clear the shoulders 12b and 12c of the upper strap member. The U-shaped rod 14 may be brought into such position by moving it upwardly a laterally spaced distance from the upper strap member 12 and it may then be moved horizontally until the hook-shaped portions 14e and 14f are disposed above the shoulders 12b and 12c of said upper strap member. It will now be observed that the holes 24 are so situated in shoulders 12b and 12c that the ends of said hook-shaped portions register with the upper ends of said holes above the ears 25. The U-shaped rod 14 may now be lowered to its Fig. 1 position and said hook-shaped portions 14e and 14f will enter said holes 24 and snap past said ears and thereby lodge in their lower ends.

The inherent tendency of the U-shaped rod or member 14 under the weight of the pipe load would be to bend its arms inwardly. This, in turn, would tend to bend the shoulders of the upper strap member 12 downwardly and inwardly. To counteract this tendency, the wedging action of the pipe against the arms of said U-shaped member 14 will tend to spread them out, thereby easing the lateral moment or strain upon the shoulders of the upper strap member 12.

By the same token, the lower ends 12d and 12e of said upper strap member will themselves abut the arms 14c and 14d of the U-shaped member 14 upon any inward movement of said arms in order to limit and resist such movement. It will be observed that the hook-shaped

members 14e and 14f extend at an angle of approximately 45 degrees to the vertical and at an angle of approximately 90 degrees to the shoulders 12b and 12c of the upper strap member. Consequently, said hook-shaped portions 14e and 14f are disposed flat against the walls of openings 24 at their lower ends. This provides a good bearing support for the hook-shaped members and also enables them to exert a camming action or force against the shoulders of the upper strap member tending to urge them outwardly. This would tend to counteract the tendency of the upper strap member to bend inwardly under the weight of the load.

Turning now to Fig. 3, it will be observed that a U-shaped or V-shaped member 40 is provided as a modified form of the U-shaped member 14 above described. The arms 40a and 40b of said member 40 extend upwardly and diverge from their lower to their upper ends. At their upper ends are hook-shaped members 40c and 40d respectively which are simply the upper ends of the arms bent inwardly and downwardly to correspond to the hook-shaped members 14e and 14f above described. The rounded yoke 40e at the bottom of member 40 has substantially the same curvature as the corresponding portion 14a of the member 14 above described and the two hook-shaped members 40c and 40d are spaced approximately the same distance apart as the hook-shaped members 14e and 14f. In effect, arms 40a and 40b simply eliminate the double bend 14b above described but in principle the member 40 is identical with the member 14 and it may be used in conjunction with the same upper strap member 12 in precisely the same manner as above described.

The foregoing is illustrative of preferred forms of this invention and it will be understood that these forms may be modified and other forms provided within the broad spirit of the invention and the broad scope of the claim.

I claim:

A pipe hanger of the character described, comprising an upper inverted U-shaped strap member and a lower U-shaped rod member supported by said strap member, and U-shaped rod member having a pair of inwardly and downwardly extending hook-shaped upper end portions and said strap member having a pair of holes formed therein to receive said hook-shaped upper end portions and thereby to engage said U-shaped rod member with said strap member, the arms of said U-shaped rod member being spaced apart a sufficient distance to clear the strap member to permit of lateral movement of said U-shaped rod member relative to the strap member in order to bring said hook-shaped upper end portions into engagement with said holes, said strap member being provided with a hole intermediate said first mentioned holes to receive a vertically disposed supporting rod and said U-shaped rod member being adapted to receive and support a horizontally disposed pipe, said upper strap member consisting of a central yoke portion and a pair of outwardly and downwardly sloping shoulders integrally connected therewith, said central yoke portion having a hole formed therein to receive a supporting rod, the holes for said hook-shaped portions being elongated and tapered in shape and provided in said shoulders, the holes in the shoulders being elongated longitudinally of the upper strap member and being provided with laterally inwardly projecting ears which are engageable with the hook-shaped portions of the U-shaped member requiring that said hook-shaped portions be snapped past said ears both when they are brought into engagement with said upper strap member and when they are moved out of engagement therewith, downwardly extending end portions being provided at the far ends of the shoulders, said downwardly extending end portions being adapted to engage the arms of the U-shaped member to prevent said arms from flexing inwardly under the weight of a load supported on the yoke of said U-shaped member.
